BREAKFRONT

Melbourne F. Smith, Jr., 101 Maehill Drive, Lenoir, N.C.

Filed Jan. 15, 1964, Ser. No. 78,215

Term of patent 14 years

(Cl. D33—19)

FIGURE 3

The back of the breakfront is substantially plain and unornamented, while the top is conventionally flat.

The dominant features of my design reside in those portions shown in full lines.

I claim:

The ornamental design for a breakfront, substantially as shown and described.
